UNITED STATES PATENT OFFICE.

ERPA H. RYON, OF WALTHAM, MASSACHUSETTS, ASSIGNOR TO CROMPTON & KNOWLES
LOOM WORKS, A CORPORATION OF MASSACHUSETTS

WEFT-REPLENISHING LOOM.

1,144,946.

Specification of Letters Patent. Patented June 29, 1915.

Application filed July 3, 1913. Serial No. 778,063.

To all whom it may concern:

Be it known that I, ERPA H. RYON, a citizen of the United States, residing at Waltham, in the county of Middlesex and State of Massachusetts, have invented certain new and useful Improvements in Weft-Replenishing Looms, of which the following is a specification.

My invention relates to weft replenishing looms, and particularly to an electric filling detector or feeler mechanism for automatic weft replenishing looms, to detect the substantial or practical exhaustion of filling in the active shuttle and put into operation the weft replenishing mechanism to supply fresh filling.

The object of my invention is to simplify and improve upon the construction of electric filling detector or feeler mechanism for weft replenishing looms.

My invention consists in certain novel features of construction of my improvements as will be hereinafter fully described.

In my improved construction of electric filling detector or feeler mechanism, I provide a feeler device comprising two members, one preferably in the form of a slide, suitably guided in a stand, and having an end adapted to enter through an opening in the front wall of the shuttle, and yieldingly engage with the filling on the bobbin in the active shuttle, on the forward movement of the lay, and move outwardly with the bobbin toward the front of the loom, as the lay beats up, and a second member in the form of a plunger, suitably mounted and carried on said slide member, and movable with, and independently of said slide, and having one end preferably of wedge shape, to extend beyond the engaging end of said slide, and adapted to engage the filling on the bobbin in the normal operation of the loom.

In case the filling on the bobbin is substantially exhausted, the engagement of the inner engaging end of said plunger with the denuded bobbin, will force outwardly said plunger, and, through intermediate connection close the electric circuit, which is normally open, and put into operation the weft replenishing mechanism to supply fresh filling to the active shuttle, all as will be hereinafter fully described.

I have shown in the drawings detached portions of a loom, and particularly the

magazine portion, and some of the operating parts of a weft replenishing loom, of the type shown and described in U. S. Letters Patents No. 972,722, of October 11, 1910, and No. 1,040,985, of October 8, 1912, with my improvements combined therewith, sufficient to enable those skilled in the art to understand the construction and operation thereof.

Referring to the drawings:—Figure 1 is a front view of a detached portion of a weft replenishing loom, and particularly the magazine portion, with my improvements in electric filling detector mechanism combined therewith, looking in the direction of arrow *a*, Fig. 2; some of the parts shown in Fig. 1 are not shown in Fig. 2. Fig. 2 is a section, on line 2, 2, Fig. 1, looking in the direction of arrow *b*, same figure. Fig. 3 is a sectional plan view, taken on line 3, 3, Fig. 1, looking in the direction of arrow *c*, same figure; some of the parts are left off in this figure, and a portion of the shuttle, with a bobbin therein, is shown in this figure. Fig. 4 corresponds to Fig. 3, but shows some of the parts in a different position, also shows the bobbin substantially denuded. Fig. 5 is a transverse section, through the slide member, on line 5, 5, Fig. 4, looking in the direction of arrow *d*, same figure, and showing the top or cover which is left off in Fig. 4. Fig. 6 is a partial section and side view of the parts shown in Fig. 3, looking in the direction of arrow *d*, same figure, with some of the parts left off, and, Fig. 7 corresponds to Fig. 6, but shows the position of the feeler slide before the lay beats up, and as the feeler enters the shuttle to engage the filling.

In the accompanying drawings, 1 is a stand secured to the loom side, not shown, 2 is a detached portion of the stationary magazine secured to and supported on the stand 1. The filling detector or feeler stand 3, is secured to the stand 1 by bolts 3'. The stand 3 carries a stud 4 having a bushing 5 thereon, secured by a nut 6, adjustably secured to the feeler bed 7, which is secured on the bushing 5 by a screw bolt 8 in the usual way.

The feeler bed or guide 7 is preferably grooved or recessed on its upper surface, to loosely receive the feeler member or slide 9, which is held in place by a cap 10, (not

shown in Figs. 3 and 4), which cap is secured to the feeler bed 7 by bolts 10'. Within the cap 10 extends a rod 11, having a screw threaded end 11', which is adapted to engage a threaded hole in the inner end of the cap 10, to be turned in or out in said hole, see Figs. 6 and 7. On the rod 11 is a helically coiled compression spring 12, which bears at one end against the outer end of the cap 10, and at its other end against a lug 9'' fast on the cover 9', secured on the top of the slide member 9, to move with said slide member. The spring 12 acts to hold the slide member 9 in its forward position, as shown in Fig. 7, until, on the forward movement of the lay, said slide is moved outwardly, by engagement of the bobbin with the inner engaging end thereof, as shown in Fig. 6.

The second member of the filling detector mechanism consists in this instance of a plunger 13, which is loosely mounted to have a longitudinal movement in a groove or recess in the slide 9, see Figs. 3 and 4. The inner engaging end of said plunger 13 is preferably made wedge shaped, and is adapted to extend beyond the inner end of the feeler slide 9 and enter between the coils of the filling on the bobbin, on the forward beat of the lay, as shown in Fig. 3. The other end of the feeler plunger 13 is screw threaded, and has thereon a check nut 14, which may be turned in either direction on said plunger 13, and engages at one end with the wall of the slide member 9, as shown in Fig. 3, to limit the outward movement of the plunger 13. The distance that the engaging end of the plunger 13 extends beyond the engaging end of the slide 9, may be regulated by turning the nut 14 on the screw threaded end of said plunger 13.

A helically coiled compression spring 15'' extends and is supported between a lug 9'' on the slide member 9, and one arm 15' of an angle lever 15. The spring 15'' acts to yieldingly hold the end 15' of the angle lever 15 against the check nut 14, on the plunger 13, and move outwardly said plunger 13, and yieldingly hold it in its outward position as long as there is any substantial amount of filling on the bobbin, as shown in Fig. 3.

The angle lever 15 is pivotally mounted on a stud 16 on the feeler slide 9. The inner end of the angle lever 15 carries a copper plug 15''', which is adapted to engage with the inner end of a strip of metal 17, which strip of metal is secured in a groove or recess in a strip of insulating material 17' secured within the recess in the slide 9, as shown in Fig. 5. The outer end of the strip 17 is connected by means of a wire 18, see Fig. 1, with a battery 19. An insulating strip 20 is secured upon the outer side of the strip 17 at its outer end, as shown in Figs. 3 and 4, to prevent said strip 17 from coming

in contact with the outer end of the feeler slide 9. To the outer end of the feeler slide 9 is secured one end of a wire or electric connector 21; the other end of said connector 21 is connected with a magnet 22, supported on a stand 23 fast on the feeler stand 3. The magnet 22 is connected with the battery 19 by a wire or connector 24, see Fig. 1.

Loosely mounted in the bearings 3'' and 3''' on the feeler stand 3 is a shaft 25. A helically coiled torsion spring 26 encircles the shaft 25, and has one end secured to the bearing 3''', and the other end secured to a collar 27 fast on the shaft 25. On one end of the shaft 25 is secured the hub 28' of an upright lever 28. The upper end of the lever 28 has pivotally connected thereto a horizontally and longitudinally moving rod 29, which is loosely guided in a stand 3.

When the angle lever 15 is moved on its pivotal support, through the inward movement of the plunger 13, by reason of said plunger engaging with the denuded bobbin, as shown in Fig. 4, and engages the metal strip 17, it closes the circuit and causes the energizing of the magnet. The energizing of the magnet will cause the upright lever 28 to be moved inwardly, against the action of the torsion spring 26, and from the position shown by broken lines to the position shown by full lines in Fig. 2.

The inward movement of the upright lever 28 will move inwardly the rod 29, causing said rod to extend into an open or slotted portion 3'' in the stand 3, and form a fulcrum for the end of the operating lever 30, which receives its motion from a cam, not shown, through a connector 31, which is provided with a rod head 31' thereon. Pivotally connected to the outer end of the lever 30 is a rod head 32' on the lower end of an upwardly extending rod or connector 32, which is connected with and operates the selecting mechanism of the weft replenishing mechanism, as fully shown and described in U.S. Letters Patent No. 1,030,748, of June 25, 1912.

The advantages of my improvements will be readily appreciated by those skilled in the art. They can be readily applied to automatic weft replenishing looms of the type referred to, and by means of the filling detector mechanism, comprising two members, one having a broad engaging edge to bear against the filling on the bobbin, and the other a wedge shaped adjustable engaging end to enter between the coils of filling on the bobbin, until the bobbin is substantially denuded, I am enabled to allow the bobbin to remain in the shuttle until substantially all of the filling is drawn off therefrom, and then, through the movement of the plunger member relative to the slide member, the electric circuit is closed, and the weft replenishing mechanism put into operation, to

transfer a new bobbin into the active shuttle, all as will be readily understood by those skilled in the art.

It will be understood that the details of 5 construction of my improvements may be varied if desired.

Having thus described my invention, what I claim as new and desire to secure by Letters Patent is:—

10. 1. In an automatic weft replenishing loom, a filling detector mechanism, comprising a member having an end to enter a slot in the shuttle and engage the filling on the bobbin or filling carrier therein, and a second member, mounted on and movable with said first mentioned member, and having an end to engage the bobbin or filling carrier in the shuttle, a magnet for controlling the weft replenishing mechanism, a normally 15 open electric circuit between said magnet and said first mentioned member, one terminal being insulated within said member, and the other terminal being a pivoted lever, and means, operated by said second mentioned member, to close said circuit, on the substantial exhaustion of filling in the active shuttle.

2. In an automatic weft replenishing loom, a filling detector mechanism, comprising 30 a slide having an end to enter a slot in the shuttle, and engage the filling on the bobbin, or filling carrier therein, and a plunger, mounted on and movable with said slide, and having an end to engage the bobbin in the shuttle, and a magnet for controlling the weft replenishing mechanism, and a normally open electric circuit, and an electric switch within said slide, operated by said plunger, to close said circuit on the substantial exhaustion of filling in the active 35 shuttle.

3. In a weft replenishing loom, filling detector mechanism, comprising a slide having an end to enter a slot in the shuttle and 40 engage the filling on the bobbin or filling

carrier therein, and an adjustable plunger, mounted on and movable with said slide, and having an end to engage the bobbin or filling carrier in the shuttle, and a magnet, and a normally open electric circuit connected therewith, operated by said plunger, to close said circuit on the substantial exhaustion of filling, and means, operated by the magnet to put into operation the filling changing mechanism. 55

4. In an automatic weft replenishing loom, a filling detector mechanism, comprising a slide having an end to enter a slot in the shuttle and engage the filling on the bobbin in the filling carrier therein, and a plunger, mounted on and movable with said slide, and having a wedge shaped end to engage the bobbin or filling carrier in the shuttle, said plunger adjustable relative to said slide, a magnet for controlling the weft 60 replenishing mechanism, a normally open electric circuit connected therewith, an electric switch within said slide operated by said plunger, to close said circuit on the substantial exhaustion of filling in the active 65 shuttle. 70

5. In an automatic weft replenishing loom, a filling detector mechanism, comprising a slide having an end to enter a slot in the shuttle and engage the filling on the bobbin or filling carrier therein, a plunger, mounted on and movable with said slide, and having an end to engage the bobbin in the shuttle, a pivoted lever operated by said plunger, a magnet for controlling the weft 75 replenishing mechanism, a normally open electric circuit, connected therewith, said circuit closed by said lever through the movement of said plunger by the bobbin on the substantial exhaustion of filling in the active 80 shuttle. 85
